WILLIAM S. SMITH, OF CAMBRIDGE, MASSACHUSETTS.

CONTROLLING SYSTEM FOR ELECTRIC ELEVATORS.

Specification of Letters Patent. Patented Dec. 11, 1917.

1,249,682.

Application filed February 5, 1916. Serial No. 76,456.

To all whom it may concern:

Be it known that I, WILLIAM S. SMITH, a citizen of the United States, residing at Cambridge, in the county of Middlesex and State of Massachusetts, have invented a new and useful Improvement in Controlling Systems for Electric Elevators, of which the following is a specification, reference being had therein to the accompanying drawings.

10 My invention relates to the electrical operation of elevators by the use of a push-button system and the main object of the invention is to provide a system which is simple and effective both in construction and in operation and which may be installed at a low cost.

Another object of the invention is to provide a system having means for preventing interference with the elevator car after it 20 has been started by the operation of a push-button and until it has reached its destination.

Additional objects of the invention will be more specifically set forth and described 25 hereinafter.

Briefly described, my invention contemplates a system for controlling electrical elevators having the following general features. A motor of any suitable construction 30 is provided for operating the elevator car in either direction, the motor being preferably arranged in a circuit across the line, the closing and opening of said circuit to start and to stop the motor being controlled 35 by a reversing-switch of suitable construction. At each floor or station is installed a push-button of ordinary construction and in the car there may be a series of push-buttons corresponding in number and arrangement to the floor or station push-buttons. 40 All of these push-buttons are included in suitable circuits adapted when any one circuit is closed by the operation of a push-button to operate the motor-controlling devices to start the motor. To prevent interference after the car has started and before it reaches its destination means are provided whereby all the push-button circuits are opened by the operation of the motor-controlling devices without interrupting the 45 operation of the motor. Until the car reaches its destination and the motor has stopped the operation of any push-button either at a station or in a car cannot close a push-button circuit and therefore is of no 50 effect.

Preferably, I accomplish these results by providing a series of floor-magnets corresponding in number to the floors or stations, each magnet having two windings or coils, 60 one being an actuating-coil for operating the magnet and the other being a retaining-coil for holding the magnet in any operated position. The actuating-coil of each magnet is included in a circuit with its respective station and car push-buttons so that the closing of a circuit by the operation of a push-button either at a station or in the car closes a circuit and actuates one of the floor-magnets which by means of suitable 65 contacts closes a second circuit which energizes a magnet for operating the reversing-switch to start the motor. The reversing-switch magnet is provided with suitable contacts so that when it is operated a new circuit is closed through the retaining-coils on the floor-magnets and the push-button circuits are all opened thereby making the 70 motor-push-buttons ineffective so far as the motor-controlling devices are concerned.

In the accompanying drawings illustrating an apparatus for controlling elevators constructed and operated in accordance with my invention Figure 1 is a diagrammatic view showing the preferred arrangement of 85 circuits and apparatus and Fig. 2 is a side elevation of one form of contacts arranged to be operated by the reversing-switch to close the retaining-coil circuit on the floor-magnets before the push-button circuits including the actuating-coils are opened.

Fig. 1 of the drawings illustrates the apparatus as adapted to be actuated by a direct current but it can be used in connection with an alternating current by a proper 95 modification of the magnet construction and the windings on the same; all of which modifications would be apparent to one versed in the art.

In the illustrated embodiment of the invention there is shown a system having four stations or floors but the number of stations or floors may be reduced or increased by merely subtracting from or adding certain 100 units to the system.

Referring to Fig. 1, 3 and 4 are the positive and negative supply lines respectively and 5 is the armature of a motor shown as a shunt motor having a field coil 6 connected to the supply lines by conductors 7 and 8, the circuit being opened and closed by a switch 9. The circuit for operating the mo-

tor is across the line as indicated by the conductors 11 and 11_a, the circuit being controlled by a reversing-switch 12 which will be described in detail hereinafter.

- 5 For the purpose of operating the reversing-switch to start the motor from any floor or station, the following means are provided. Suitable circuit-closing devices such as push-buttons a_1 , a_2 , a_3 and a_4 are located 10 at the four floors or stations respectively. When the elevator car is employed for carrying passengers a similar series of push-buttons b_1 , b_2 , b_3 , and b_4 is installed in the car. The hoistway door on each floor is provided with a contact c_1 , c_2 , c_3 and c_4 respectively, which is open when the door is open and closed when the door is closed so that 15 the system is out of operation unless all the hoistway doors are closed.
- 20 Arranged in the push-button circuits are a plurality of coils d_1 , d_2 , d_3 and d_4 , corresponding in number to the number of floors or stations; said coils being wound with sufficient ampere turns to actuate small floor 25 magnets e_1 , e_2 , e_3 and e_4 respectively.
- The push-buttons at the stations when operated close a circuit from the main 3 through conductor 13, door contacts c_1 , c_2 , c_3 and c_4 , provided they are all closed, conductor 14, thence through the coil d corresponding to the push-button operated, conductor 15, contacts 16, contact member 17, contact 18, conductor 19, contact 20, contact member 21, contact 22 and conductor 23 to 35 the negative main. The contact members 17 and 21 are operated by the reversing-switch to open the push-button circuits for reasons and in a manner to be hereinafter explained. When the system is in a normal 40 inoperative condition, the contact members are in a position closing the push-button circuits across the contacts 16 and 18 and the contacts 20 and 22. The door contacts are so arranged in this circuit that if any door 45 is opened the circuit cannot be closed by the operation of a push-button. The latter are in parallel circuits, each push-button being adapted to close a circuit through its respective coil to actuate its respective floor magnet. When car push-buttons are employed, 50 they are placed in parallel circuits with their respective push-buttons at the stations and connected by flexible conductors 24 to those circuits, so that the effect of operating 55 a push-button in the car is the same as when a station push-button is operated.

The operation of a floor-magnet due to the pressing of a push-button at a station or in the car operates the reversing-switch to 60 start the motor in the following manner. The magnets e_1 , e_2 , e_3 and e_4 are provided with contact members f_1 , f_2 , f_3 and f_4 , respectively which engage contacts g_1 and h_1 , g_2 and h_2 , g_3 and h_3 and g_4 and h_4 respectively 65 when any magnet is energized and thereby

establishes a control circuit through various conductors and switches j_1 , j_2 , j_{2a} , j_3 , j_{3a} and j_{4a} which operate to direct the control circuit to the reversing-switch to start and to stop the motor. These switches are operated 70 by a member C arranged to travel in synchronism with the car and as shown in Fig. 1 the member C moves to the right when the car ascends and to the left when it descends. The control circuits adapted to be 75 established by the various floor-magnets may be divided into two main groups, first, a group connecting the switches j_1 , j_2 and j_3 with the contacts g_1 , h_1 , and g_2 , h_2 and g_3 , h_3 respectively so that the operation of magnet 80 e_1 , or e_2 or e_3 closes a circuit to cause the car to descend and, secondly, a group connecting the switches j_{2a} , j_{3a} and j_{4a} with the contacts g_2 , h_2 and g_3 , h_3 and g_4 , h_4 respectively in order that the operation of magnet 85 e_2 or e_3 or e_4 closes a circuit to cause the car to ascend.

The reversing-switch 12 may be of any suitable construction and is shown diagrammatically in Fig. 1 as composed of two magnets k and k_1 , each carrying suitable contacts for closing the motor circuit. The magnet k is included in the first group of control circuits and when it is operated by the closing of any one circuit in this group 90 by the operation of floor-magnet e_1 or e_2 or e_3 contact-pieces 25 and 26 carried by the magnet are moved into engagement with contacts 27 and 28 and contacts 29 and 30 respectively and thereby closes the motor 100 circuit and admits the current to the motor in such a way as to cause the car to descend. The magnet k_1 is included in the second group of control circuits and when operated by the closing of any one circuit in this 105 group through the operation of floor-magnet e_2 or e_3 or e_4 contact-pieces 32 and 33 carried by the magnet are thrown into engagement with contacts 34 and 35 and contacts 36 and 37 respectively and in consequence 110 closes the motor circuit and admits the current to the motor in such a way as to cause the car to ascend.

Both groups of control circuits may be connected to the positive main 3 by a common conductor 40 connected to conductor 14 and through the door contacts to conductor 13 and may be connected to the negative main 4 by a common conductor 41. Between the points 42 and 43 the control 120 circuits are parallel.

As thus far described, it will be noted that all the push-button circuits are capable of being closed by the operation of any push-button. In order to prevent the interference which would be caused by the operation of a push-button after the motor starts and before the car reaches its destination, I provide means for maintaining all of the push-button circuits open from 130

the time the reversing-switch is operated until after the car has reached its destination. At the same time I also provide means for maintaining the particular floor-magnet which has been operated by the pushing of the push-button to start the motor in an operative position until the car reaches its destination, otherwise the opening of all the push-button circuits would permit the operated floor-magnet to return to an inoperative position and thereby break the control circuit established to start the motor and the motor would stop. While any suitable means may be employed for opening all the push-button circuits and maintaining the operated floor-magnet in its operative position, I prefer to accomplish these results by providing each floor-magnet with a retaining-coil having sufficient ampere turns, when energized, to maintain the magnet in an operated position, but not of sufficient strength to operate it, all of these retaining-coils being in a circuit which is closed and opened by means of contacts carried by the reversing-switch magnets. All of the push-button circuits are likewise opened by means of contacts carried by the reversing-switch magnets when the reversing-switch is operated to start the motor. In the drawings 30 r_1, r_2, r_3 and r_4 designate the retaining-coils on the magnets e_1, e_2, e_3 and e_4 respectively. All of the retaining-coils are connected in series although if desired they may be connected in parallel. These coils are connected to the positive main through the conductor 14, door contacts and conductor 13 and on the other side are connected to the negative main through conductor 45 and conductor 23. The conductor 45 is connected 35 to a contact 47 on the magnet k_1 and a contact 48 on the magnet k and conductor 23 is connected to contact 46 on the magnet k_1 and contact 49 on magnet k the result being that when either of said magnets is operated the retaining-coil circuit is closed by the contact-member 17 in k_1 or the contact-member 21 in k . At the same time the operation of either one of these magnets causes the contact-piece 17 or 21 to move out of engagement with the contacts 16 and 18 or 20 and 22 and to open all of the push-button circuits. It is, of course, necessary that in the operation of either of the reversing-switch magnets the retaining-coil circuit should be established before the push-button circuits are opened and for this purpose I provide a form of movable contact shown in Fig. 2 of the drawings in which the contact 16 is 40 in the form of a pivoted arm held against the contact member 17 by means of a spring 53. As the contact-piece 17 is moved upwardly the contact 16 follows it through the medium of the spring 53 until it is stopped by the stop 52. At this point the contact-piece 17, shown in dotted lines in Fig. 2 in this position, engages the contact 46 which is likewise in the form of a pivoted arm held in a downward position by a spring 54 and provided with an ear 55 to limit its downward movement. At this point the contact-member 17 is in engagement with both contacts 16 and 46 and at this point all of the push-button circuits are closed and also the retaining-coil circuit. The contact-piece 17 has, however, only partially completed its movement and as it continues to move upwardly carrying the contact 46 into the position shown by dotted outlines, it separates from the contact 16 and thereby opens all 50 of the push-button circuits. Its uppermost position is maintained so long as the magnet k_1 is in position to close the motor circuit and when the magnet k_1 is deenergized the contact-piece retraces its movement, 55 breaking the retaining-coil circuit and closing the push-button circuit to the position shown in Fig. 2 in full lines. It is, of course, necessary that this form of contact be duplicated for the other contacts on the retaining-coil and the push-button circuits on the reversing-switch. The operation of my device is as follows. Assume that the car is in the position indicated in the drawings by the controller C; 95 that is, at the third floor and that a person at the second floor desires to call the car to that floor or a person in the car wishes to go to the second floor. The person presses the push-button a_2 or b_2 , as the case may be, for an instant and then releases the pressure. The operation of the button, if any one of the elevator doors is open produces no effect because the contact on the door which is open is not closed, but if all the doors are closed then a circuit is made from the positive main 3 through conductor 13, door contacts c_4, c_3, c_2 and c_1 , conductor 14, coil d_2 , push-button a_2 or b_2 , as the case may be, through conductor 15 to contact 16, contact 17, contact 18, conductor 19, contact 20, contact member 21, contact 22 and conductor 23 to the negative main 4. This circuit being established the current in coil d_2 causes the magnet e_2 to operate and puts the contact-piece f_2 across the contacts g_2 and h_2 . This establishes another circuit from the positive main through conductor 13, door contacts, conductor 14, conductor 40 to point 100 42, coil k , switch j_1 , conductor 60, switch j_2 , conductor 61, contact h_2 , contact-piece f_2 , contact g_2 , conductor 41 to the negative main. This circuit operates the magnet k and starts the motor in a direction to cause the car to descend. The operation of the magnet k at the same time moves the contact member 21 from engagement with contacts 20 and 22 into engagement with contacts 48 and 49. This action of the magnet k breaks the push-button circuits be- 110 120 125

tween the contacts 20 and 22 and establishes a new circuit through the retaining-coils r_1 , r_2 , r_3 and r_4 on the magnets e_1 , e_2 , e_3 and e_4 respectively. This circuit is from the positive main through the conductor 13, door contacts c_4 , c_3 , c_2 and c_1 , conductor 14 to retaining coils r_1 , r_2 , r_3 and r_4 , conductor 45, contact 48 contact piece 21, contact 49 and conductor 23 to the negative main. The retaining-coils through which the current flows when this circuit is closed are of sufficient strength to hold the magnets e_1 , e_2 , e_3 and e_4 in any position in which they may be when the circuit is closed but are not of sufficient strength to operate any of said magnets. The magnet e_2 , having been operated by coil d_2 by the closing of the push-button circuit by pressing button a_2 or b_2 , is consequently held in its operative position when the retaining-coils are energized by the closing of the last described circuit. It is of course necessary that the circuit through the retaining-coils be closed before the push-button circuit is opened in order that the operated magnet may be retained in an operative position. If the push-button circuit were opened in advance of the closing of the retaining-coil circuit then the magnet would drop back into inoperative position breaking the reversing-switch circuit and stopping the motor. For these reasons, I use the form of contacts shown in Fig. 2 and thereby the push-button circuits are not opened until the retaining-coil circuit has been closed. The operation of the reversing switch having in the manner just described closed the retaining-coil circuit and opened all the push-button circuits, the operation of any push-button will not establish any circuits and therefore any interference with the elevator while it is in operation is prevented.

Current having now been supplied to the motor in such a manner as to cause the car to descend, the member C starts to travel and moves with a speed relative to the speed of the car in a direction corresponding to the down direction of the car (as shown in Fig. 1 from right to left). Moving in this direction, the member C first engages the switch j_{3a} and closes it. This produces no effect as this switch is in the second group of control circuits governing the car when ascending. Continuing in its movement to the left the member C next engages switch j_2 and opens same, thereby opening the circuit which was established through the contacts g_2 , h_2 on the magnet e_2 and the switch j_2 when the push-button was operated to call the car to the second floor. In consequence, the magnet k returns to an inoperative position opening the motor circuit and the motor comes to rest with the car at the second floor and the member C between the switches j_{2a} and j_2 . In this posi-

tion the operation of push-buttons a_2 or b_2 have no effect because the fact that both switches j_{2a} and j_2 are open prevents a circuit being established through magnets k or k_1 even if the magnet e_2 operates to close a circuit through g_2 , h_2 by the contact-piece f_2 . When the magnet k returns to an inoperative position, the contact-piece 21 carried thereby disengages from contacts 48 and 49 opening the retaining-coil circuit and engages contacts 20 and 22 closing the push-button circuits and the system is then in a normal position ready to be again started by the pressing of a push-button at a floor station or in the car.

The car is now at rest at the second floor. Assume that it is desired to bring the car to the fourth floor. This can be done in two ways; either by a person at the fourth floor pressing push-button a_4 or by a passenger in the car pressing push-button b_4 . The result is the same in either case. When the push-button is operated, it establishes a circuit as hereinbefore described except that coil d_4 is excited instead of coil d_2 and magnet e_4 is operated which closes a circuit from the positive main 3, through conductor 13, door contacts, conductor 14, conductor 40 to point 42, coil k_1 , conductor 62, switch j_{4a} , conductor 64, contact h_4 , contact-piece f_4 , contact g_4 , conductor 41 to the negative main 4. This circuit operates the magnet k_1 and admits current to the motor in such a way as to cause the car to ascend. The operation of the magnet k_1 also causes the contact-member 17 to move into engagement with contacts 46 and 47, thereby closing the circuit through the retaining coils hereinbefore described and to disengage the contacts 16 and 18 thereby opening all of the push-button circuits. As the car starts to ascend from the second floor the member C moves to the right (as shown in Fig. 1) first closing switch j_2 , which produces no effect as this switch is in the first group of control circuits governing the car when descending. The member C then reaches switch j_{3a} and opens it which also is barren of effect because this switch is not in the control circuit which was closed by the operation of the floor-magnet e_4 . The switch j_3 is next closed and finally the member C reaches switch j_{4a} , opens it and breaks the control circuit causing the magnet k_1 to return to an inoperative position and the motor to stop with the car at its destination, the fourth floor. From the foregoing description the operation of my system will be apparent irrespective of the number of floors to which it may be applied.

It is to be observed that my system is of great simplicity both in construction and in operation and for this reason combines great efficiency with low cost of installation and maintenance.

It is to be understood that my invention may be embodied in other forms of construction than that herein shown and described and except where specifically limited in the following claims, it is my intention to claim it broadly.

What I claim is:—

1. In an apparatus for controlling elevators, the combination with a motor for operating the car in either direction of a reversing-switch, a push-button for each floor or station, a magnet for each floor, each floor-magnet being provided with an actuating-coil in circuit with its respective push-button and being provided with a retaining-coil, a suitable circuit including the retaining-coils on the said floor magnets and means whereby said last mentioned circuit is closed and said push-button circuits are opened whenever said reversing-switch is operated to start the motor.

2. In an apparatus for controlling elevators, the combination with a motor for operating the car in either direction of a reversing-switch for starting and stopping the motor, a push-button for each floor or station, a magnet for each floor or station, each of said magnets having an actuating-coil and a retaining-coil, suitable push-button circuits, each of said circuits including one of said push-buttons and an actuating-coil upon its respective magnet, a circuit including all of said retaining-coils and means operated by the operation of said reversing-switch for closing said retaining-coil circuit and opening all of said push-button circuits.

3. In an apparatus for controlling elevators, the combination with a motor, a car and a plurality of stations of a reversing-switch, a plurality of floor-magnets corresponding in number to said stations, each of said floor-magnets having an actuating-coil and a retaining-coil, each of said actuating-coils being in a circuit with its respective station, contacts closed by the operation of any one of said floor-magnets to establish a circuit to operate said reversing-switch, a circuit including said retaining-coils on said floor-magnets and means actuated by the operation of the reversing-switch for closing said circuit through said retaining-coils and for opening all the circuits between said stations and the actuating-coils of said floor-magnets.

4. In an apparatus for controlling elevators, the combination with a motor, a car and a plurality of stations of a reversing-switch, floor-magnets corresponding in number to said stations, each of said floor-magnets having an actuating-coil and a retaining-coil, suitable circuits each including a station and the actuating-coil upon its respective floor-magnet, means for closing said circuits to actuate said magnets, a

circuit including the retaining-coils in said magnets and means operated by the reversing-switch for closing said retaining-coil circuit and for opening all of the actuating-coil circuits.

70

5. In an apparatus for controlling elevators, the combination with a motor for operating the car in either direction of a reversing-switch, a push-button for each floor, a magnet for each floor, each floor-magnet 75 being provided with an actuating-coil and a retaining-coil, the actuating-coil of each of said floor-magnets being in circuit with one of said push-buttons, means actuated by the operation of any of said floor-magnets for operating said reversing-switch to start the motor and means actuated by the operation of said reversing-switch for energizing the retaining-coils of said magnets and for opening the push-button circuits.

85

6. In an apparatus for controlling elevators, the combination with a motor for operating the car in either direction of a reversing-switch, a plurality of floor-magnets 90 one for each floor or station, each of said floor-magnets having an actuating-coil and a retaining-coil in different circuits, a plurality of push-buttons one for each floor or station, each in circuit with an actuating-coil on one of said floor-magnets, means operated by the operation of said floor-magnets to establish a circuit for actuating the said reversing-switch to start the motor and means actuated by the operation of the reversing-switch for opening the circuit to the actuating-coils of the floor-magnets and for closing a circuit through the retaining-coils of the floor-magnets.

95

7. In an apparatus for controlling elevators, the combination with a motor for operating the car in either direction of a reversing-switch, a floor-magnet for each station, each floor-magnet having an actuating-coil and a retaining-coil, a push-button 105 for each station, suitable circuits whereby the operation of a push-button closes a circuit through the actuating-coil of its respective floor-magnet, contacts closed by the operation of the floor-magnets to establish a circuit through an actuating-coil of the reversing-switch to operate the same and means actuated by the operation of the reversing-switch for opening all the push-button circuits to the actuating-coils of the floor-magnets and for closing a circuit 110 through the retaining-coils of the floor-magnets.

115

8. In an apparatus for controlling elevators, the combination with a motor for operating the car in either direction of a reversing-switch, a push-button for each floor, a magnet for each floor, each floor-magnet being provided with an actuating-coil and a retaining-coil, the actuating-coil 125 of each of said floor-magnets being in circuit

130

- with one of said push-buttons, means actuated by the operation of any one of said floor-magnets for operating said reversing-switch to start the motor and contacts 5 actuated by the operation of said reversing-switch for energizing the retaining-coils of said magnets and for opening the push-button circuits.
9. In an apparatus for controlling elevators, the combination with a motor for operating the car in either direction of a reversing-switch, a plurality of floor-magnets one for each floor or station, each of 10 said floor-magnets having an actuating-coil 15 and a retaining-coil in different circuits, a plurality of push-buttons one for each floor or station, each in circuit with an actuating-coil on one of said floor-magnets, means operated by the operation of said floor-magnets to establish a circuit for actuating the 20 said reversing-switch to start the motor and contacts actuated by the operation of the reversing-switch for opening the circuit to the actuating-coils of the floor-magnets and for

closing a circuit through the retaining-coils 25 of the floor-magnets.

10. In an apparatus for controlling elevators, the combination with a motor for operating the car in either direction of a reversing-switch, a floor-magnet for each 30 station, each floor-magnet having an actuating-coil and a retaining-coil, a push-button for each station, suitable circuits whereby the operation of a push-button closes a circuit through the actuating-coil of its respective floor-magnet, contacts closed by the operation of the floor-magnets to establish a circuit through an actuating-coil of the reversing-switch to operate the same and contacts actuated by the operation of the reversing-switch for opening all the push-button 40 circuits to the actuating-coils of the floor-magnets and for closing a circuit through the retaining-coils of the floor-magnets.

In testimony whereof, I hereunto set my hand this second day of February, 1916.

WILLIAM S. SMITH.
